ATTORNEY

UNITED STATES PATENT OFFICE.

BRUCE FORD, OF PHILADELPHIA, PENNSYLVANIA.

SECONDARY OR STORAGE BATTERY.

1,238,755.

Specification of Letters Patent.

Patented Sept. 4, 1917.

Application filed February 3, 1915. Serial No. 5,828.

To all whom it may concern:

Be it known that I, BRUCE FORD, a citizen of the United States, and a resident of Philadelphia, in the county of Philadelphia and State of Pennsylvania, have invented 5 certain new and useful Improvements in Secondary or Storage Batteries, of which the following is a specification.

The principal object of the present invention is, first, to provide an improved secondary or storage battery for submarine, portable, vehicle and like uses, and second, to provide for laterally supporting the bottom parts of plates in respect to their container without increasing the hazard of short-circuiting by sediment.

The invention will be claimed at the end hereof, but will be first described in connection with the embodiment of it chosen 20 for illustration in the accompanying drawings, in which—

Figure 1, is an elevational view, principally in section.

Fig. 2, is a transverse section taken on the 25 line 2—2 of Fig. 1.

Fig. 3, is a perspective detail view, and Fig. 4, and Fig. 5, are detail views.

In the drawings 1 is a container wholly or partly of insulating material. 2 are 30 plates of one polarity suspended in the container, for example, by means of ledges and hook-like fastenings 3 at one top edge and rods 4 at the other top edge. These plates 2, of one polarity, are provided at 35 their bottoms with wide portions 5 abutting upon the container walls 6. The plates 7, of the opposite polarity, are suspended in the manner described and at their bottoms are narrower than the wide portions 5 of the plates 2. These plates 7 are provided 40 below the wide portions 5 with downwardly projecting feet 8 abutting upon the container wall 6. 9 are separators, preferably wider than the narrow plates, thus projecting beyond the edges of the plates, and they are 45 interposed between the plates and may be supported by rods 10 passing through the feet 8.

The feet 8 and the wide portions 5 evidently steady the plates and prevent them from shifting laterally in respect to the container. The level to which sediment may rise in the space 11 at the bottom of the container is limited only by the distance between the bottom of the container and the

bottom edge of the plates, because even if the sediment rises so as to reach the feet 8 no bridging that would result in short-circuiting occurs because the feet 8 are all of the same polarity. The widened portions 5 are even with or above the level of the bottom edges of the plates so that they cannot be bridged in connection with the feet until the level of the sediment rises above the bottom edge of the plates. Furthermore 65 there is no place for sediment to lodge where it can bridge across between plates of unlike polarity by reason of the construction which has been described. It may be said that the plates are laterally steadied in respect to the container, while at the same time the sediment space is not restricted nor is there danger of the sediment bridging between plates of like polarity. If the container is not of insulating material it 70 may be lined with rubber or the like, or the plates of one polarity or all the plates may be equipped with insulating saddles 12 and 13.

The top surfaces of the feet 8 are arranged 75 below the bottom edges of the wider plates 5, hence if sediment should drop downward at the edges of the plates and lodge upon the top surfaces of the feet it could not by spreading sidewise cause a short-circuit, but 80 would on the contrary fall between the feet and drop down or else it might bridge the adjacent feet, but since the feet would be of the same polarity no harm would be 85 done.

It will be obvious that modifications may be made in details without departing from the spirit of the invention, which is not limited in regard to such matters.

What I claim is:

1. In a storage battery the combination of plates of opposite polarity, feet projecting laterally from the plates of one polarity beyond the side edges thereof and below the lower edges of the plates of opposite polarity, and separators having their lower edges extending below the lower edges of the last mentioned plates, substantially as described.

2. In a storage battery the combination of a container, plates of opposite polarity suspended therein and provided respectively with lateral and downward projections arranged at different levels and adapted to abut upon the walls of the container, the downward projections engaging the walls

of the container below the bottoms of the plates of opposite polarity, substantially as described.

3. In a storage battery the combination of 5 plates of opposite polarity, feet projecting laterally from the plates of one polarity beyond the side edges thereof and below the lower edges of the plates of opposite polarity, separators having their lower edges ex-

tending below the lower edges of the last 10 mentioned plates, and rods through the feet to support the separators.

In testimony whereof I have hereunto signed my name.

BRUCE FORD.
